UNITED STATES PATENT OFFICE.

EDWIN ROAT, OF BUFFALO, NEW YORK, ASSIGNOR OF ONE-HALF TO
HARRY HAMLIN, OF SAME PLACE.

FEED-DRIER.

SPECIFICATION forming part of Letters Patent No. 249,677, dated November 15, 1881.

Application filed June 8, 1881. (No model.)

To all whom it may concern:

Be it known that I, EDWIN ROAT, a citizen of the United States, residing at Buffalo, in the county of Erie and State of New York, have 5 invented certain new and useful Improvements in Feed-Driers; and I do hereby declare the following to be a full, clear, and exact description of the invention, such as will enable others skilled in the art to which it appertains to make and use 10 the same, reference being had to the accompanying drawings, and to letters or figures of reference marked thereon, which form a part of this specification.

My invention relates to apparatus for drying 15 not only what is known among maltsters, distillers, and starch and grape-sugar manufacturers as "feed," but also solid grain, cornmeal, &c.

A cylinder provided with longitudinal buckets has before been used for drying feed, &c., 20 in connection with a single hot-air flue, upon which it revolves. A similar revolving cylinder, with steam-drum secured in the interior and revolving with it, has also before been used. A system of steam-pipes with buckets attached 25 to the outer pipes has also been revolved inside of a stationary cylinder for the same purpose. The above devices have failed to dry the feed, &c., in a complete and satisfactory manner.

In carrying out my invention I have taken 30 the cylinder with longitudinal buckets and provided it with a system of parallel steam-pipes, connected at their ends with hollow drums or heads, and have placed these pipes at such a distance from the interior surface of the cylinder or from the edge of the buckets as to allow 35 quite a fall for the feed before striking the heated pipes, thereby effecting a thorough separation of the particles to be dried and allowing a more complete evaporation of the moisture.

40 The further evaporation of the moisture thrown off from the drying feed is assisted by a current of heated air, which is produced by passing the condensed steam through a coil of pipe located in an inclosing-chamber. The air thus 45 heated is caused to pass, by means of a suitable ventilating-flue, through the cylinder and in contact with the drying feed. Another important feature of my improved drier is that by inclosing the revolving cylinder in a chamber and admitting cold air therein I am enabled

5 to heat this air from the radiated heat of the outer surface of the cylinder, and pass it through said cylinder and in contact with the feed, thereby utilizing all the heat which has heretofore been wasted.

55

In the drawings, Figure 1 is a central longitudinal section of my improved apparatus. Fig. 2 is a transverse section. Fig. 3 is a perspective view of the same, with portions of the inclosing-cylinder broken away to show the interior.

60 Referring to the drawings, *a* is the cylinder, which is slightly inclined and mounted upon wheels or rollers *b*. It is revolved upon these rollers by means of a gear-wheel, *c*, operated by 65 suitable power. Longitudinal buckets *d*, for lifting the feed, are riveted to the interior surface of the revolving cylinder. Two hollow drums or heads, *e* *e'*, are secured inside of the cylinder, at or near either end thereof, by means 70 of a suitable number of brackets, *e*², and adjusting-screws *e*³. The interior surfaces of these drums are perforated to admit a series of connecting-pipes, *f*. Steam is admitted to drum *e* by means of a supply-pipe, *g*, and an exhaust-pipe, *g'*, is fitted to drum *e'* for conveying the 75 condensed steam to a coil of pipe, *g*², located in the inclosing-chamber *h*. This chamber incloses the entire cylinder, and is provided with a partition, *h'*, which serves to prevent the 80 heated air from passing out through the ventilating-flue *k*³ before it has passed through the cylinder, where it is utilized in the drying process.

85 *k* is a diaphragm extending nearly to the top of chamber *h*, and serves to direct the lighter particles of feed (which are carried by the current of heated air) into the passage *k'*, where they fall and are collected at the point *k*². By this arrangement I am enabled to save 90 a considerable portion of feed which would otherwise pass away through the ventilating-flue *k*³ and be lost.

95 *l* is a hopper, and *l'* a chute, by means of which the feed is introduced into the cylinder. The dried feed is discharged from the cylinder through hopper *m*.

100 *n n* are openings in the side of the inclosing-chamber for the admission of air.

The operation of my device is as follows: The

feed is introduced into the cylinder through the chute, and is carried up and dropped upon the heated pipes, and, falling between said pipes to the bottom of the cylinder, is again lifted in 5 the same manner as before. This operation is repeated until the feed gradually works toward the lower end of the cylinder, where it is discharged.

The distance between the edges of the buckets and the outer pipes is an important feature 10 of my device, as by these means a more complete separation of the moist particles of feed is effected. By means of the coil of pipe g^2 , into which the condensed steam passes, I am 15 enabled to heat a current of air introduced into the chamber h from the outside through openings n , and by means of my ventilating-flue pass such current of heated air through the cylinder to operate in further drying the 20 feed. The inclosing-chamber h , by means of its partition h' , enables me to utilize the radiated heat of the cylinder (which has heretofore been wasted) and effect a more complete 25 drying of the feed than has ever before been accomplished by the old forms of driers.

I claim—

1. In a feed-drier, the combination, with an inclined revolving cylinder, provided with buckets, of a system of steam-pipes located in and revolving with said cylinder, and means 30 for collecting and utilizing in the drying process the heat from the condensed steam and the radiated heat of the cylinder, substantially as shown and described.

2. In a feed-drier, the combination of cylinder a , hollow drums or heads e e' , pipes f f' and g g' , coil g^2 , inclosing-chamber h , with partition h' , diaphragm k , passage k' , and ventilating-flue k^3 , substantially as shown and described. 35

3. In a feed drier, as a means of collecting 40 and saving the lighter particles of feed, the chamber h , with its partition h' , the diaphragm k , passage k' , and ventilating-flue k^3 , substantially as shown and described.

EDWIN ROAT.
